US0D1053372S

(12) United States Design Patent (10) Patent No.: US D1,053,372 S
(45) Date of Patent: * Dec. 3, 2024

(54) ACUPRESSURE MAT SET

(71) Applicant: Ningbo Lvshan Trading Co., Ltd.,
Ningbo (CN)

(72) Inventor: Na Li, Zhejiang (CN)

() Term: 15 Years

(21) Appl. No.: 35/519,100

(22) Filed: Nov. 10, 2023

(80) Hague Agreement Data

Int. Filing Date: Nov. 10, 2023

Int. Reg. No.: DM/233113

Int. Reg. Date: Nov. 10, 2023

Int. Reg. Pub. Date: Nov. 24, 2023

(51) LOC (14) Cl. 24-01

(52) U.S. Cl.

USPC D24/200

(58) Field of Classification Search

USPC D24/215, 200, 211, 212, 213, 214, 133,
